UNITED STATES PATENT OFFICE.

EARL V. HUGHES, OF PERU, INDIANA.

DESIGN FOR A RADIOCABINET.

Application filed February 27, 1929. Serial No. 30,243. Term of patent 3½ years.

To all whom it may concern:

Be it known that I, EARL V. HUGHES, a citizen of the United States, residing at Peru, in the county of Miami and State of Indiana, have invented a new, original, and ornamental Design for a Radiocabinet, of which the following is a specification, reference being had to the accompanying drawing, forming part thereof.

The figure is a perspective view of a radio

cabinet showing my new design, one of the sliding front doors being entirely open and the opposite door being in closed position, there being exposed a portion of the inner front panel through the door opening.

I claim:

The ornamental design for a radiocabinet as shown and described.

EARL V. HUGHES.
